UNITED STATES PATENT OFFICE.

FRIDOLIN SCHIMMEL, OF FARIBAULT, MINNESOTA.

COMBINATION TABLE AND WRITING DESK.

Application filed October 20, 1924. Serial No. 744,642.

My invention provides an extremely simple and highly efficient combination table and writing desk adapted for use in the guest rooms of hotels and various other 5 places; and, generally stated, the invention consists of the novel devices and combinations of devices hereinafter described and defined in the claims.

In the accompanying drawings, which 10 illustrate the invention, like characters indicate like parts throughout the several views.

Referring to the drawings:

Fig. 1 is a perspective view, showing the complete combined table and writing desk 15 adjusted for use as an ordinary table;

Fig. 2 is a view corresponding to Fig. 1, but with some parts broken away and with the shiftable top section adjusted for use as a writing desk;

Fig. 3 is a transverse section on the line 20 3—3 of Fig. 2;

Fig. 4 is a front-to-rear section on the line 25 4—4 of Fig. 2; and

Fig. 5 is a perspective showing the shiftable top section or board turned upside down.

The table has a rectangular box-like body made up of a rectangular marginal frame 6 and a bottom 7, which bottom, in the particular illustration, is not extended completely 30 to the back of the table but is terminated short thereof and connected to a transverse partition board 8, the ends of which are rigidly attached to the side rails of the frame 6. At its corners, the frame 6 has rigidly attached supporting legs 9 of any suitable design.

The table top is made up of a fixed board or section 10 and a shiftable board or section 40 11, the latter being preferably considerably wider than the former. The fixed section 10 is rigidly secured to the frame 6 by screws, nails or otherwise. The shiftable top section or board 11, at its central portion, is 45 rigidly secured to the solid part 12 of a guide arm that works slidably through a notch in the transverse partition 8 and slides freely in a guideway formed between parallel rails 13 and 14 that are rigidly secured to the partition 8, to the bottom boards 7 and to the front rail of the frame 6. The rail 13 is thicker than the rail 14 and is formed with a guide groove 15, for an important purpose. The rear end of the guide bar 12 is notched 50 to afford a reduced rear end extension, to

the top of which a small metallic guide clip 16 is rigidly but detachably secured, preferably by a wood screw 17. The front end of the guide bar 12 is notched or reduced at its under side to form a top front end extension 18, to the bottom of which another metallic guide clip 19 is rigidly but detachably secured, preferably by a wood screw 20. The two guide clips 16 and 20 project from the same side of the guide bar and work 60 in the guide groove 15 of the guide bar 13. The guide bar 12 is shown as rigidly attached to the sliding board or top section 11 by wood screws 21 and 22 applied as best shown in Fig. 4, by reference to which it 65 will also be noted that, when the board 11 is in normal position, the projecting rear end of the guide bar 12 is forced onto the beveled upper edge of an abutment block 23. When the rear end of the bar 12 is thus 70 forced onto the abutment block 23, the front edge of the board 11 will be pressed tightly down upon the front rail of the frame 6 and held so that it will not be raised from said frame even if the table be lifted by application of power to the front edge of said 75 board 11.

In connection with the guide bar 12 and other parts described, a latch should be provided for normally holding the shiftable top section 11 in the position shown in the drawings, Figs. 1 and 4; and as an important feature of this invention, I combine a latch bar for such purpose, with the guide bar 12 and utilize the same as a supplemental guide or extension of said guide bar. This I accomplish in the most effective way by forming the said latch bar 23 as an integral extension of said bar 12 and by making the said combined bar of wood, such as maple. The latch-forming portion 23 of the said bar is cut quite thin as it approaches its junction with the main bar 12 and is so formed that it will act as a spring and normally press the free end of the latch bar 23 downward or 80 away from the front edge portion of the board 11, as best shown in Fig. 4. The extreme free end of the latch bar 23 is projected to form a finger piece 23^a, and just inward of said finger piece, it is notched to afford a latch shoulder 23^b. The undersurface of the bar 23 is gradually rounded or cut so that when the body 11 has been drawn out, as shown in Fig. 2, and its end forced 85 rearward or to closed position, the said latch 90 100 105 110

bar 23 will cam itself back into interlocking engagement with the bottom surface of a notch 24, which is cut in the front rail of the frame 6 to afford a passage for the bar 5 23. Obviously, when the board 11 is slid to normal position, it will be there locked by the latch bar 23. When the board 11 is to be drawn out, as shown in Fig. 2, the lock shoulder 23^b may be readily raised into 10 engagement with the notch 24 by pressing upward on the finger piece or knob 23^a of the latch lever 23 and then, of course, the said board 11 may be freely drawn out to the 15 position stated. Throughout all of these adjustments, the board 11 will be held in a true horizontal position by engagement of the clips 16 and 19 with the guide groove 15.

The notch 24 is only of such width that the latch bar 23 will slide freely therethrough 20 and, hence, the said latch bar 23 affords a guide for holding the extensible table board 11 for true sliding movements. In fact, with the arrangement described, the combined bars 12-23 act as a continuous guide bar or 25 rail for holding the table top 11 for true sliding movements, and this guide bar extends not only under the entire board 11 but far to the rear thereof. The latch bar 23, therefore, performs the double function of latch bar and guide bar, and the bar 12 forms a double function of guide bar under sliding operations and as a board-depressing bar when engaged with the abutment 23.

When the board 11 is drawn out as shown 30 in Fig. 2, it affords a convenient writing table, which has much greater leg clearance than the frame 6, and it also opens up the two compartments A and B formed within the framework of the table. These compartments are adapted to contain various articles, 35 such as writing materials, pens, ink, pencils, books and the like, which, when the board 11 is adjusted back to normal position, will be readily covered up and closed from view.

The location of the guide bar and guiding 40 means for the slidable table top section or board at the approximate center thereof is important for several reasons. In the first place, it affords guiding means less liable to cramping and binding actions than guides located at opposite sides of the table, and in the second place, by eliminating the side guides, it makes it possible to form the table top of any suitable design, either square, oblong, polygonal beyond the number of four sides, round, or oval. As shown, only one of the sections of the table top is made slidable, but the same principle of construction might be applied to both of the table top sections. 45 Of course, if desired, an extension or filling board may be used to fill in the space between the separated top sections 10 and 11, thereby adapting the table to be used as an extension table. If, at any time, it should be desirable 50 to remove the extensible board 11 from the

table, this may be most conveniently done simply by removing the screws 17 and 20 from the guide clips 16 and 19, respectively, in which case the combined guide and latch bar 12-23 would come off with said board 55 11. As is evident, the screw 20 can be reached by a screw driver inserted upward through the bottom of the guide channel formed between the guide bars 13 and 14, while the screw 7 can be reached from the 60 top by the screw driver when the board 11 is drawn out as shown in Fig. 2.

What I claim is:

1. The combination with a table frame having a bar guide, of a table top including a slideable board, a guide bar secured to said slideable board and working in said guide and holding said board for true sliding movements, and a latch bar attached to the under side of said slideable board in alignment with said guide bar and constituting a supplemental guide and having interlocking engagement with said table frame to hold said slideable board in normal position.

2. The combination with a table frame formed with a centrally located guide channel and provided with a table top, one section of which is slideable, and a guide bar secured to the under side of said slideable board and working in said guide channel, said guide bar having a forward vertically resilient extension operating as an auxiliary guide and having means for engagement with said table frame to latch said slideable board in normal position.

3. The combination with a table frame formed with a centrally located guide channel and provided with a table top, one section of which is slideable, and a guide bar secured to the under side of said slideable board and working in said guide channel, said guide bar having a forward vertically resilient extension operating as an auxiliary guide and having means for engagement with said table frame to latch said slideable board in normal position, the said guide and resilient extension being formed integral and of wood and the extended portion thereof being inclined for camming action on the table frame under movements of said slideable board from extended to normal position.

4. The combination with a table frame provided with centrally located bars spaced to afford a guide channel with an open bottom, at least one thereof having a longitudinal guide groove, of a table top, at least one section of which is slideable into a position in which its major portion extends outward of said frame, and a guide bar secured to the under side of said slideable top section and provided with detachable front and rear detachable guide clips working in said guide groove and holding the table top against vertical movements, said clips being detachable from said guide bar, the one through

the open bottom of the guide channel and the other through the open top thereof, when said slidable top section is extended.

5. The combination with a table frame formed with a central guide channel, of a table top, at least one section of which is slidable, and a guide bar secured to the under side of the slidable top section, projecting rearwardly therefrom and working in said guide channel and having a vertically resilient forward extension operating as an auxiliary guide and having interlocking engagement with said frame to latch said slid-
10 able top section in normal position.

6. The combination with a table frame ¹⁵ formed with a guide channel, of a table top, at least one section of which is slidable, and a guide bar secured to the under side of the slidable top section, projecting rearwardly ²⁰ therefrom and working in said guide channel and having a vertically resilient forward extension operating as an auxiliary guide and having interlocking engagement with said frame to latch said slidable top section in normal position. ²⁵

In testimony whereof I affix my signature.

FRIDOLIN SCHIMMEL.
